US0D1070776S

(12) **United States Design Patent** (10) Patent No.: **US D1,070,776 S**
(45) Date of Patent: ** *Apr. 15, 2025

(54) **CONNECTOR**

(71) Applicant: **Molex, LLC**, Lisle, IL (US)

(72) Inventors: **Muttanna Belle**, Bengaluru (IN);
Sandeep Cs, Bengaluru (IN); **Harsha Thyagaraj**, Bengaluru (IN)

(73) Assignee: **Molex, LLC**, Lisle, IL (US)

(*) Notice: This patent is subject to a terminal disclaimer.

(**) Term: **15 Years**

(21) Appl. No.: **29/858,161**

(22) Filed: **Oct. 28, 2022**

(51) LOC (15) Cl. **13-03**

CLAIM

The ornamental design for a connector as shown and described.

DESCRIPTION

FIG. 1 is a front top perspective view of a connector showing our new design;

FIG. 2 is a front bottom perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a rear view thereof.

The even-length broken line portion of the figure drawings depict portions of the connector that form no part of the claimed design.

1 Claim, 6 Drawing Sheets
